METAL TRIMMING MACHINE

Henry Earl Morton, Muskegon, and Homer B. Clark, Muskegon Heights, Mich.

Application June 7, 1944, Serial No. 539,076

7 Claims. (Cl. 90—24)

1

Our present invention relates to improvements in metal trimming machines, and particularly to metal trimming machines for removing protuberances inadvertently produced on the surfaces of sheet metal when welding the ends or edges thereof together; and the objects of improvement are: first, to provide a metal trimming machine of novel and improved structure; second, to provide a metal trimming machine whereby protuberances can be removed from the surface or surfaces of sheet metal cleanly; third, to provide a metal trimming machine whereby metal protuberances can be removed from sheet metal quickly; fourth, to provide a metal trimming machine whereby metal protuberances at opposite sides of metal sheets can be removed simultaneously; fifth, to provide a metal trimming machine whereby metal protuberances can be removed from surfaces of curved metal cleanly; sixth, to provide a metal trimming machine whereby metal protuberances can be removed from metal surfaces having irregular shapes; seventh, to provide a metal trimming machine that will be simple in construction and easy to operate.

We attain these named objects, and such other objects as appear from a perusal of the following description assisted by the accompanying drawing of our metal trimming machine, in which—

Figure 1 is a side elevation view of our entire metal trimming machine;

Figure 2 a rear elevation view showing the major portion of our metal trimming machine in cross-section and the upper trimming cutter arranged to traverse an arc bowed upward intermediate its ends.

Figure 3 a front elevation view of the metal trimming machine of which the upper trimming cutter is arranged to traverse an arc bowed upward intermediate its ends as similarly shown in Figure 2;

Figure 4 a fragmentary view of the machine showing the upper trimming cutter arranged to traverse an arc bowed upward at its ends;

Figure 5 a fragmentary view of the machine showing the upper trimming cutter arranged to be reciprocated on a straight course;

Figure 6 an enlarged side view of the trimming cutter supporting ramps with the trimming cutters mounted therein as in the act of removing protuberances from a vehicle wheel rim, and including the shaft and bearing for supporting the lower cutter ramp;

Figure 7 a top plan view of the lower trimming cutter supporting ramp with the lower trimming cutter mounted therein;

2

Figure 8 an under side view of the upper trimming cutter supporting ramp with the upper trimming cutter mounted therein;

Figure 9 a cross-sectional view of the upper and lower trimming cutters as in the act of removing protuberances from the outer and inner peripheries of a vehicle wheel rim simultaneously.

Throughout the several views of the accompanying drawing illustrating our metal trimming machine, similar numerals refer to similar parts of the machine, and referring thereto:

Numerals 1 refers to the base portion of the machine housing, 2 the intermediate portion of the housing and 3 the upper portion on which is mounted fluid pressure cylinder 4 closed at its upper end by cover 5 and having piston 6 therein mounted on the upper end of piston rod 7 having secured to its lower end cross-head 8 provided with two downwardly extending arms 9 at each of its ends, the said downwardly extending arms 9 each having an upwardly extending link 10 pivotally connected to its lower end and of which there are four, each pivotally connected to longitudinal shifting frame 11.

25 The said longitudinal shiftable frame 11 has cross members 12 connecting its side members together in spaced apart relation to each other, and between the said cross members upper protuberance trimming cutter supporting ramp 13 having a groove machined in its lower work facing side and extending longitudinally of the ramp in inclined relation to the side members of the frame and the ramp, and in which groove is held by key 13' the upper trimming cutter 14 whereby

30 35 the metal protuberance 15 is removed from the sheet of metal herein shown as of vehicle wheel rim 16 for convenience.

Numeral 17 refers to the lower trimming cutter supporting ramp, having extending from its rear end shaft 18 oscillatorily supported in bearing 19. The said ramp having machined in its periphery and in inclined relation to its axis, groove

40 45 50 in which is held by key 21 the lower trimming cutter 22 for removing protuberance 23 at the inner periphery of the vehicle wheel rim 16 by forward cutting movement of the cutter 22, which has an upward arched reciprocal movement imparted to it by the shaft 18 oscillated in bearing 19 by collar 24 adjustably secured to reduced diameter portion 25 of the shaft 18 and having arms extending therefrom.

Within the base portion 1 is fluid pressure cylinder 26 into which is admitted fluid under pressure past the fluid control valve 27 and against 55 the under side of piston 28 for reciprocating the

said piston in the cylinder, and by its pivotal connection with link 29 connected to arm 30 extending from collar 24 imparts oscillatory motion to the shaft 18, ramp 17 and lower trimming cutter 22, and by the link 32 pivotally connected to arm 33 of the collar 24 and lever 34 of the shaft 34' and second lever 35 on said shaft and pivotally connected to link 36 connected to boss 37 of the longitudinal shiftable frame 11 supported by swingable link 10, causes the frame to reciprocate as shown in Figures 2 and 3 on an arc bowed upward intermediate its ends and flatter than the arc traversed by the lower trimming cutter during its protuberance trimming operation.

The piston rod 1 of the piston 6 has cross-head 38 secured to it above the cross-head 8 for guiding the piston rod in slideways 39 provided with tapered gibs 40 for aligning the piston rod and thereby the cross-head.

The cross-head 8, as shown in Figures 2 and 3, in addition to the downwardly extending arms 9 have (which as shown consists of a vehicle wheel rim) work clamping members 41 extending downward from cross members 42 engaging the work and clamping said work against the supporting members 43 extending upward from the bearing 19.

Numerical 44 refers to the lever by which the valve 27 is operated to admit fluid under pressure through ports 45 and 46 to the cylinder 26 to move the piston 28 in the cylinder 26, and pipe 47 provides means whereby the said fluid under pressure is conducted to the valve 27 and therefrom through ports 45 and 46 to the cylinder 26 to move the piston 28 in the direction desired to operate the trimming cutters 14 and 22 in their respective cutting and reverse movements by the mechanism therefor as previously described.

Numerical 48 refers to the valve operated by lever 49 admitting and controlling fluid under pressure to cylinder 4 through ports 50 and 51 for operating the piston 6 therein, and 52 the pipe for conducting the said fluid to the valve 48.

Broken lines 53 and 54 shown in Figures 7 and 8, represent the angular relation of the cutting edges of the trimming cutters 14 and 22 during their protuberance trimming or removal from the metal, and which angular relation permits the protuberances to be removed by cutting with the least consumption of power.

In Figure 4 the metal trimming cutter 14 is shown as mounted on the ramp 13 forming a part of shiftable frame 55 which is supported from above by the four links 56 pivotally connected to the cross-head 57 at 58, and is guided in its longitudinal movement by guide members 59 extending downward from the cross-head which by reason of links 56 pivoted above the frame is caused to travel on an arc having its two ends bowed upward. The longitudinal movement of the frame 55 ramp 13 and trimming cutter 14 is caused by like linkage mechanism as connected to the arm 33 of the collar 24 secured to the reduced diameter of shaft 18 and boss 27 extending from the shiftable frame as shown in Figures 2 and 3.

In Figure 5 the metal trimming cutter 14 is shown as mounted on the ramp 13 forming a part of shiftable frame 60 which is slidable in a pair of slideways 61 located below the cross-head at each of its ends, and by reason of the slideways the frame, together with the ramp 13 and trimming cutter 14, is caused to slide during its shifting movement in a straight line and to shift re-

ciprocatively in the slideways 61 by like linkage mechanism as connected to the arm 33 of the collar 24 secured to the reduced diameter portion 25 of the shaft 18 and the boss 37 extending from the frame, as shown in Figures 2, 3 and 4.

In performing the operations of trimming or removing metal protuberances from work such as the welded sheet metal herein shown and described as the rim of a vehicle wheel (having provided the metal trimming machine substantially as described and the wheel rim having protuberances at its outer and inner peripheries) it is placed on supporting members 43 with the protuberances uppermost, and fluid under considerable pressure, such as one hundred pounds or more per square inch, is then admitted by valve 48 through port 50 to the cylinder 4 and against the upper side of piston 6, thereby forcing the piston, piston rod and cross-head 8 downward and the work clamping members 41 against the vehicle wheel rim 16 and thereby clamping the wheel rim onto the work supporting members 43. Having clamped the wheel rim onto the supports 43 as described, fluid under considerable pressure is admitted by valve 27 through port 46 to the upper side of piston 28 in cylinder 26, thereby forcing the piston 28 downward and by the link 29 extending from the piston 28 and connected to arm 30 of the collar 24, turns the collar 24, shaft 18 and lower trimming cutter ramp and trimming cutter 22 through the cut and thereby severs the protuberance 23 from the inner periphery of the vehicle rim, and by the long link 32 connected to the arm 33 of the collar 24, lever 34 on shaft 34', lever 35 on said shaft 34', link 36 connected to boss 37 of the longitudinal shiftable frame 11, moves the shiftable frame 11 longitudinally of the cross-head 8, and thus carries the upper trimming cutter 14 mounted on ramp 13 through the cut of the protuberance 15 at the outer periphery of the wheel rim and thereby severs the said protuberance from the rim.

Both trimming cutters 14 and 22, as shown in Figures 2 and 3, travel an arc path with the path of the upper trimming cutter bowed upward intermediate its ends and having a greater radius than the radius of the outer periphery of the wheel rim, and the radius of the path traversed by the lower trimming cutter is less than the radius of the inner periphery of the wheel rim.

While the cutting movement of the trimming cutters have been described as of one direction when removing a protuberance from each cutter, it is to be understood that the direction of travel can be reversed by merely reversing the cutter 14 in the slot of the ramp 13, and the cutter 22 reversed in the slot 21 of the ramp 17, and that the direction of the cutters can be the same when removing protuberances from very thin sheet metal.

Having described our present invention, the rights thereto we desire to secure by Letters Patent are defined in the following claims therefor.

We claim:

1. A metal trimming machine comprising, a rotatable ramp mounted on a horizontal axis having a metal trimming cutter extending therefrom, a vertically removable crosshead, means for moving the crosshead vertically, a horizontally shiftable frame, a pair of links pivotally mounted on the crosshead in spaced parallel relationship and extending substantially vertically upwardly therefrom, the shiftable frame pivotally attached to the upper ends of the pair of links, an upper ramp having a metal trimming cutter extending down-

wardly therefrom secured to the shiftable frame, and means for shifting the shiftable frame on the pivoted links when the first mentioned ramp is rotated.

2. A metal trimming machine comprising, a supporting frame, a lower ramp rotatably mounted on a horizontal axis on the frame having a metal trimming cutter extending substantially upwardly therefrom, means for rotating the ramp, a crosshead mounted for vertical movement on the frame above the ramp, means for moving the crosshead vertically, a pair of links pivotally connected to the crosshead at spaced horizontal locations and extending upwardly therefrom, a horizontally shiftable frame pivotally connected to the upper ends of the links at equally spaced horizontal locations, an upper ramp having a metal trimming cutter secured thereto and extending downwardly therefrom secured to the shiftable frame, and means for shifting the shiftable frame on the pivoted links when the lower ramp is rotated.

3. A metal trimming machine comprising, a supporting frame, a lower ramp rotatably mounted on a horizontal axis on the supporting frame and having a metal trimming cutter secured thereto and extending substantially upwardly therefrom, means for rotating the ramp, a pair of spaced work supporting members supported on the supporting frame each side of the ramp, a crosshead mounted on the supporting frame above the lower ramp for vertical movement toward and away from the lower ramp, a pair of similarly located work clamping members secured to the crosshead and extending downwardly therefrom, a pair of links pivotally connected to the crosshead in spaced parallel upwardly extending relationship, a shiftable frame pivotally supported on and between the upper ends of the pair of links, a link and crank connection between the lower ramp and the shiftable frame for shifting the frame horizontally when the lower ramp is rotated.

4. A metal trimming machine comprising, a rotatable supporting ramp having a metal trimming cutter extending upwardly therefrom and having an arm extending therefrom, a fluid pressure cylinder having a piston therein operated by fluid pressure in the cylinder, a link pivotally connected between the arm and the piston for rotating the ramp, a horizontally shiftable frame supported above the ramp for vertical movement, means for moving the shiftable frame vertically, a metal trimming cutter secured to the shiftable frame and extending downwardly therefrom, and means for shifting the shiftable frame horizontally when the ramp is rotated.

5. A metal trimming machine comprising, a supporting frame, a metal trimming cutter pivotally mounted on the supporting frame on a horizontal axis, means for rotating the cutter, a crosshead supported on the supporting frame above the cutter for vertical movement, means for

moving the crosshead vertically, a horizontally shiftable frame supported on the crosshead for horizontal movement thereon, a second metal trimming cutter secured to and extending downwardly from the shiftable frame, and means connected between the shiftable frame and the first mentioned cutter for shifting the shiftable frame horizontally when the first mentioned cutter is rotated.

6. A metal trimming machine comprising, a supporting frame, a tool head rotatably mounted on the supporting frame on a horizontal axis, a metal trimming tool secured to and extending substantially upwardly and slightly spirally of the tool head, a hydraulic ram supported on the supporting frame, a link and arm connection between the hydraulic ram and the tool head for rotating the tool head thereby, a crosshead supported on the supporting frame for vertical movement above the tool head, a second hydraulic ram supported on the supporting frame connected to the crosshead to impart vertical movement thereto, a pair of links pivotally connected to the crosshead in spaced relationship each side of the tool head and extending upwardly in parallel relationship, a shiftable frame pivotally connected to the upper end of each of the links, a second tool head secured to the shiftable frame above the first mentioned tool head, a metal trimming tool secured to and extending downwardly and slightly angularly to the second mentioned tool head, and a link and crank connection between the first mentioned tool head and the shiftable frame for shifting the frame horizontally on the pair of links when the first mentioned tool head is rotated.

7. A metal trimming machine as described in claim 6 including a pair of work supporting members one each side of the first mentioned tool head, and work clamping members secured to the crosshead in vertical alignment with the work supporting members adapted to clamp a cylindrical work piece therebetween when the crosshead is moved downwardly for trimming superfluous metal therefrom.
